ASHTRAY

Bo Lennart Ljungberg, 23 L. Södergatan, Lund, Sweden

Filed Apr. 25, 1968, Ser. No. 11,610

Claims priority, application Sweden Oct. 27, 1967,
303/67

Term of patent 14 years

Int. Cl. D27—03

U.S. Cl. D85—2

FIG.1

FIG.2

FIG. 1 is a view in perspective of the ashtray in accordance with my design comprising a tray with flat sides forming a receptacle for the ash, and a top with longitudinal curved grooves crossing each other, leaving between the crossings flat tops and provided with holes at the places where the grooves are crossing.

FIG. 2 is a view showing the ashtray from above.

I claim:

The ornamental design for an ashtray, as shown and described.
